[57] CLAIM

The ornamental design for a cooktop, as shown and described.

DESCRIPTION

FIG. 1 is a perspective view of a first cooktop showing the design;

FIG. 2 is a plan view of the first cooktop of FIG. 1; FIG. 3 is a side elevation of the first cooktop of FIG. 1; FIG. 4 is an end elevation of the first cooktop of FIG. 1; FIG. 5 is a perspective view of the first cooktop of FIG. 1 with one burner module and grate removed to receive other attachments;

FIG. 6 is a perspective view of a second cooktop showing the design;

FIG. 7 is a plan view of the second cooktop of FIG. 6; FIG. 8 is a side elevation of the second cooktop of FIG. 6; FIG. 9 is an end elevation of the second cooktop of FIG. 6; and,

FIG. 10 is a perspective view of the second cooktop of FIG. 6 with one burner module and grate removed to receive other attachments.

The cooktops are intended to be built in and the underside is not part of the design and is shown in phantom. The back side not illustrated is a mirror image of the front side in each instance.
